UNITED STATES PATENT OFFICE.

FRANK J. VLCKEK AND ANTONIN PLACEK, OF CLEVELAND, OHIO, ASSIGNEES TO THE VLCKEK TOOL COMPANY, A CORPORATION OF OHIO.

TOOL-QUENCHING TANK AND THE LIKE.

Application filed October 16, 1920. Serial No. 417,304.

To all whom it may concern:

Be it known that we, FRANK J. VLCKEK and ANTONIN PLACEK, the former a citizen of the United States and the latter a citizen 5 of Czechoslovakia, both residing at Cleveland, in the county of Cuyahoga and State of Ohio, have invented certain new and useful Improvements in Tool-Quenching Tanks and the like, of which the following is a 10 specification.

This invention relates to tool quenching tanks and the like, and has for its main object to provide a tank for quenching tools after being heated for tempering same, 15 which is provided with means for conveying the tools therefrom. Said means consists of a rotatably mounted drum having inwardly extending strips forming pockets for carrying and delivering the tools into a 20 chute.

In order that the invention may be clearly understood, the same will be hereinafter fully described in connection with the accompanying drawings, and the novel features 25 thereof will be particularly pointed out in the appended claims.

In the drawings similar characters of reference are used to indicate corresponding parts.

30 Figure 1 is a section elevation of a quenching tank constructed in accordance with our invention,

Fig. 2 is a cross section of the drum taken on line 2—2 of Fig. 1, and

35 Fig. 3 is a similar view illustrating a modification.

Referring to the drawings, 1 represents a tank constructed of sheet metal or other suitable material for containing oil or other 40 quenching fluid into which tools to be tempered are dropped. In order to automatically remove the tools after being dropped into the quenching fluid, a longitudinally arranged drum 2 is rotatably mounted 45 upon rollers 3, 4 and 5 carried by the sides of the tank. Said drum is provided with rings 6 and 7 for supporting it upon said rollers, and the bottom of the drum is located below the top of the tank and is 50 adapted to rotate under the quenching fluid in the tank. Any suitable means may be employed for rotating the drum, as for instance a driving pinion 8 meshing with a ring rack or spaced rollers at 9. One end

of the drum 2 is provided with a circular 55 opening 10 for receiving a chute 11 for guiding the tools into the bottom of the drum and the other end with a similar opening 12 for permitting a delivery chute 13, which is arranged within said drum, to extend therefrom. The upper end of the delivery chute 13 is supported at 14 and its lower end at 15. Fixed to the inner sides 60 of the drum 2 are longitudinally extending strips 16 which have their inner or free 65 edges bent toward the inner sides of the drum and upwardly with relation to its direction of rotation for forming pockets 17 for carrying the tools to the delivery chute 13. The tools fall from the receiving chute 11 into the bottom of the drum 2 between the strips 16, and as the drum revolves counter-clockwise, said strips 16 or pockets 17 formed thereby carry the tools 70 upwardly and when the pockets are over 75 the delivery chute, the tools slide therefrom into said chute.

In some cases when it is desirable to employ a drum of large diameter as 18 and 80 rotate said drum slowly, and use a wide delivery chute as is indicated at 19, longitudinal strips 20 instead of 16 are fixed to the inner sides of the drum. The strips 20 are similar to the strips 16 except that their inner or free edges are bent downwardly at 21, which form pockets at 22 and others at 23. The tools as before fall into the bottom of the drum between the strips 20 and are carried upwardly by the pockets 22, and when they are at the top of the drum 85 and over said delivery chute, some of the tools slide therefrom into said chute and others fall into the pockets 23 of the next forward strip and may slide therefrom into said chute but from the opposite direction. 90

In operation the tools pass down the receiving chute 11 into the quenching fluid in the bottom of the drum 2, and the rotation of the drum causes its side strip 16 to lift the tools into the delivery chute 13. 100

Having fully described our invention, what we claim is:

1. In a tool quenching tank and the like, the combination of a tank for holding a fluid, a drum, the drum being rotatably 105 mounted, the lower part of the drum being adapted to pass through the fluid, a delivery chute extending from the upper part

of the drum, the delivery chute extending the entire length of the drum, and the drum having means for carrying tools to the delivery chute, substantially as described.

5 2. In a tool quenching tank and the like, the combination of a tank for holding a fluid, a drum, the drum being rotatably mounted, the lower part of the drum being adapted to pass through the fluid, a delivery

10 chute extending from the upper part of the drum, the delivery chute extending the entire length of the drum, and strips fixed to the inner sides of the drum for carrying tools into the delivery chute, substantially

15 as described.

3. In a tool quenching tank and the like, the combination of a tank for holding a fluid, a drum, the drum being rotatably mounted, the lower part of the drum being

20 adapted to pass through the fluid, a delivery chute extending from the upper part of the drum, the delivery chute extending the entire length of the drum, strips fixed to the inner sides of the drum, and the strips be-

25 ing bent toward the inner sides of the drum and upwardly with relation to its direction of rotation for forming pockets for carrying tools into the delivery chute, substan-

30 tially as described.

30 4. In a tool quenching tank and the like, the combination of a tank for holding a

fluid, a drum, the drum being rotatably 35 mounted, the lower part of the drum being adapted to pass through the fluid, a delivery chute extending from the upper part of the drum, strips fixed to the inner sides of the drum, and the strips being bent 40 toward the inner sides of the drum and upwardly with relation to its direction of rotation and then downwardly for forming upper and lower pockets for carrying tools upwardly and directing them into said de- 45 livery chute, substantially as described.

5. In a tool quenching tank and the like, the combination of a tank for holding a fluid, a drum, the drum being rotatably 50 mounted, the lower part of the drum being adapted to pass through the fluid, the drum having openings in its ends, a receiving chute entering the drum through one end opening, a delivery chute arranged above the receiving chute and extending the en- 55 tire length of the drum and through the other end opening of the drum, and the drum having means for carrying tools to the delivery chute, substantially as de- 60 scribed.

In testimony whereof we affix our signatures.

FRANK J. VLCKEK.
ANTONIN PLACEK.
